UNITED STATES PATENT OFFICE.

FRANK E. EICHELBERGER, OF MUSCATINE, IOWA.

LUBRICANT-STICK HOLDER.

Application filed April 28, 1922. Serial No. 557,234.

To all whom it may concern:

Be it known that FRANK E. EICHELBERGER, citizen of the United States, residing at Muscatine, in the county of Muscatine and State 5 of Iowa, has invented certain new and useful Improvements in Lubricant-Stick Holders, of which the following is a specification, reference being had therein to the accompanying drawings.

10 The invention relates to lubricant stick holders particularly adapted to be disposed over a drive pinion of a tractor in such a manner that a stick of lubricant carried thereby will engage the pinion during the 15 rotation thereof and lubricate the pinion during its rotation.

A further object is to provide a lubricant stick holder formed from a single sheet of material bent to form a cylindrical member 20 for the reception of a stick of lubricant and bent to form attaching flanges and spaced webs.

With the above and other objects in view the invention resides in the combination and 25 arrangement of parts as hereinafter set forth, shown in the drawing, described and claimed, it being understood that changes in the precise embodiment of the invention may be made within the scope of what is claimed 30 without departing from the spirit of the invention.

In the drawing:—

Figure 1 is a side elevation of a portion of a conventional form of tractor showing the 35 device applied thereto.

Figure 2 is a perspective view of the stick holder.

Figure 3 is a horizontal sectional view taken on line 3—3 of Figure 1, and showing 40 a portion of the tractor and drive pinion.

Referring to the drawing, the numeral 1 designates a portion of a tractor of conventional type and 2 the drive pinion thereof, which drives the wheel 3 through a drive 45 gear 4. It has been found extremely difficult to maintain the pinion 2 and the drive gear 4

lubricated, therefore to overcome this difficulty the lubricant stick holder 5 is provided for the reception of the lubricant stick 6.

The holder 5 is formed from a single sheet of material, bent to form the substantially cylindrically shaped stick receiving portion 7, in which the stick of lubricant 6 is received, and at 8 to form rearwardly extending spaced flanges 9 for offsetting the cylindrical portion 7, and at the same time allowing the diameter of the portion 7 to be varied for preventing binding of standard sized lubricant sticks 6. The flanges 9 terminate in outwardly extending flanges 10 which engage the side of the tractor 1 and are secured thereto by means of screws 11, in such a manner that the holder is supported in a vertical position whereby the lubricant stick 6 will easily feed downwardly into engagement with the drive pinion 2. It will be seen that as the drive pinion 2 revolves, the stick 6 will lubricate the same and that the gear 4 will also be lubricated.

From the above it will be seen that a lubricant stick holder is provided which is formed from a single sheet of material, thereby allowing the same to be cheaply made and sold.

The invention having been set forth what is claimed as new and useful is:—

A lubricant holder formed from a single piece of sheet metal bent upon itself to form a cylindrical portion for the reception 80 of a lubricant stick, outwardly extending flanges in spaced relation to each other and angularly disposed flanges carried by the outer ends of the outwardly extending flanges, said spaced flanges forming means 85 whereby when forced apart or together said cylindrical portion may be enlarged or contracted for receiving and holding different sizes of lubricant sticks.

In testimony whereof I hereunto affix my 90 signature.

FRANK E. EICHELBERGER.
